UNITED STATES PATENT OFFICE.

LAURENCE J. BERKELEY, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

COMPRESSOR UNIT.

Application filed March 17, 1923. Serial No. 625,734.

To all whom it may concern:

Be it known that I, LAURENCE J. BERKELEY, a citizen of the United States, residing at Milwaukee, in the county of Milwaukee, and State of Wisconsin, have invented a certain new and useful Improvement in Compressor Units, of which the following is a full, clear, concise, and exact description, reference being had to the accompanying drawings, forming a part of this specification.

My invention relates to systems for supplying compressed fluid, and more specifically to a unitary compressing and storing equipment, especially suitable for service in connection with stations supplying free air for blowing up or inflating automobile tires, stone cutting establishments, boiler works, in short, wherever simplicity, compactness, and durability, are material factors in the service to be rendered by the device.

A complete unit for delivering compressed fluid, necessarily comprises a prime mover, a compressor, a storage receptacle, and the necessary control devices for governing the operations of the prime mover and compressor. Where two or more separately mounted base plates are required to support different parts of the complete equipment, the services of a competent construction engineer are necessary to instal the units. Especially, in units of moderate capacity, the expense of installation thus becomes an abnormally large portion of the total expense of the unit to the user, and in case it is desired to move the equipment, this additional expense must be incurred a second time.

I eliminate the disadvantages hereinabove set forth, by uniting all parts of the apparatus into a single unitary device, of such compactness and simplicity, that any one with sufficient intelligence to stand the unit right end up and shelter it from the weather can secure satisfactory service therefrom.

Further detailed objects and advantageous features of construction of my device will become apparent as the description proceeds.

In the accompanying drawings:

Figures 1 and 2 are elevations of a device constructed according to my invention looking at the side and at the end of the unit respectively.

Figure 3 is a section on line 3—3 of Figure 1, and

Figure 4 is a plan view of the base, with the storage receptacle removed.

In the embodiment of my invention selected for illustration, the tank 10 functions, not only as a receptacle for the compressed fluid, but as a column upon which all the other parts of the complete equipment are supported. A base or pedestal 12 is bolted to the bottom of the tank 10 as at 14, the bolt passing through a central boss supported by ribs 16. A peripheral pocket 18 formed by a ledge 20 receives the lower end of tank 10 and cooperates with bolt 14 to hold the parts together.

A laterally projecting shelf 22, forming an integral part of base 12 carries upwardly projecting lugs 24 to which a platform 26 is pivoted carrying the prime mover 28 which is illustrated as an electric motor. Another shelf 30 has integrally formed diverging arms 32 each embracing part of the periphery of tank 10, and is clamped to the tank by a U-bolt 34 passing through suitable apertured bosses 36 at the ends of arms 32. Three vertical brace rods 38 extend from base 12 up through shelf 30 to cooperate with the clamping U-bolt 34 and unite the shelf base, and tank into a rigid unitary structure.

An air compressor indicated as a whole by the reference character 40 and having an air intake 42 and a fly wheel 44 is mounted on shelf 30. A belt 46 passes around fly wheel 44 and the pulley carried by the electric motor 28. It will be apparent that the weight of motor 28 and platform or shelf 26 operates to automatically maintain belt 46 under a proper tension.

A governor, indicated as a whole by the reference character 48, and a pressure regulating and control valve indicated as a whole by reference character 50, are mounted directly on tank 10, by means of suitable piping, the governor in the embodiment illustrated being located at the top of the tank, and the pressure regulating valve or the side of the tank near the top. Pipe 52 conveys the compressed fluid to tank 10. Governor 48 controls the starting and stopping of motor 28, and for this purpose, the lead lines delivering electrical power to the motor extend from the governor downward thereto, being housed in a protecting pipe 110.

56. The outlet for the air is through the pressure regulating and control valve 50 which permits the pressure of the air to be set at a predetermined value lower than the 6 pressure in the tank 10. By turning the handle of the control valve to one control position, the reducing valve is by-passed and by throwing the handle to a third position, the air may be delivered to a special 10 outlet, such as a tire filling hose as disclosed and claimed in the co-pending application of Burton S. Aikman, Serial No. 493,566, filed August 19, 1921. The unit herein shown is adapted to be employed for a farm 15 pumping system of the faucet controlled pneumatic displacement type. Movement of the control handle to either abnormal position at once functions to operate the governor to start the compressor.

20 It will be seen that I have provided a self-contained unitary device, which only needs to be stood right end up and connected to a source of electrical power and an air hose, to be in shape for immediate service.

25 Without further elaboration, the foregoing will so fully explain the gist of my invention, that others may, by applying current knowledge, readily adapt the same for use under various conditions of service, 30 without eliminating certain features which may properly be said to constitute the essential items of novelty involved, which items are intended to be defined and secured to me by the following claims.

35 I claim:

1. In combination, an elongated storage receptacle supported on end, a base for supporting the receptacle and having means of connection therewith, a horizontal support having mounting means embracing the receptacle spaced above the bottom thereof, a pump mounted on said support for filling said receptacle and a prime mover mounted on the base beneath the support for driving 45 the pump.

2. In combination, a storage receptacle, a pump associated therewith, a base for supporting the receptacle on end, and having a boss in the bottom thereof, means for securing the receptacle to the base through the medium of the boss, and a support outstanding from the receptacle and having arms and securing means embracing the same, the said support carrying the said pump.

3. A mounting of the character described comprising a base adapted to support a tank or reservoir on end, with a portion projecting beyond the tank, said base having a flange adapted to embrace the outer surface of the tank and providing a peripheral pocket to receive the lower end of the tank, a boss centrally connecting the bottom of the tank to the base, a shelf horizontally supported in spaced relation above

the base and connected thereto, said shelf having means to embrace the tank and a pump for filling the said tank mounted on the said shelf.

4. A mounting of the character described 70 comprising a base having a ledge forming a peripheral pocket to receive the lower end of a tank, the tank and base having cooperative bosses, connecting means between the bosses, the base projecting beyond the tank, upright brace rods arranged on the projecting portion of the base, a shelf supported on the upper ends of said brace rods, and clamping means embracing the tank and connected to the shelf. 75

5. In combination, a vertical cylindrical tank, a base member clamped to the bottom of the tank, said base member having a laterally extending portion forming a platform, a shelf member above said platform, a circumferential rod clamping the shelf to the tank, a compressor based on the shelf posts connecting the shelf and the platform, a motor pivoted on the platform, a driving belt, said motor and compressor being connected to each other through said belt which forms the means for supporting the weight 80 of the motor. 85

6. In combination, a vertical cylindrical tank, a base member clamped to the bottom of the tank, said base member having a laterally extending portion forming a platform, a shelf member above said platform, a circumferential rod clamping the shelf to the tank, a compressor based on the shelf, 90 and a motor operatively connected to the compressor. 100

7. A mounting of the character described comprising a base adapted to support a tank, a lateral extension on said base, means for connecting the tank to the base, a shelf above said laterally extending portion of the base and having arms embracing the tank, means connected to the arms to clamp the shelf to the tank, vertical braces between the shelf and lateral extension of the base to jointly connect the tank, base and shelf, a pump on the shelf, a governor and a regulating valve supported on said tank and operatively connected to each other and the pump, a vertically movable platform mounted on the lateral extension beneath the shelf, and a prime mover on said platform belt-connected to said power unit. 110 115

8. In a unitary structure, in combination, a tank, a pump unit operatively connected with the tank, supporting brackets on opposite sides of the tank and clamped thereto, said brackets including a horizontally extending shelf on which said pump unit is 120 mounted and secured, a base for the tank, and means securing said brackets and shelf to the base. 125

9. A unitary structure comprising, in combination, a tank, a pump unit opera- 130

tively connected with the tank, supporting brackets on opposite sides of the tank, one of said brackets being extended to form a shelf, said brackets being connected for 5 clamping the same to the tank, supporting the latter in position and supporting the shelf-forming bracket in an outstanding position, and additional sustaining means for the shelf-forming bracket.

10 10. In combination, a tank having a concaved bottom wall, a pump unit supported by the tank, a boss projecting downwardly

at the center of said concaved bottom wall, a base having a ledge forming an interior seat for receiving the lower peripheral edge 15 of the tank and centering the latter on the base, a spider on the base having ribs and a central boss, and a stud extending through and into the bosses to anchor the tank to the base. 20

In testimony whereof, I hereunto subscribe my name this 5th day of November, 1921.

LAURENCE J. BERKELEY.
